UNITED STATES PATENT OFFICE.

JENNIE FAIRFIELD, OF DETROIT, MICHIGAN.

PLOW.

1,392,133.

Specification of Letters Patent. Patented Sept. 27, 1921.

Application filed May 16, 1919. Serial No. 297,473.

To all whom it may concern:

Be it known that I, JENNIE FAIRFIELD, a subject of the King of Great Britain, residing at Detroit, in the county of Wayne and 5 State of Michigan, have invented certain new and useful Improvements in Plows; and I do hereby declare the following to be a full, clear, and exact description of the invention, such as will enable others skilled 10 in the art to which it appertains to make and use the same.

This invention relates to plows, and more particularly to a plow of the motor type.

One of the main objects of the invention 15 is to provide a walking plow of simple construction and operation, and means for propelling the same, this propelling means being capable of being used for transporting the plow from one field to another. A further 20 object is to provide a plow of the character stated, in which the greater part of the weight will be positioned at the rearward end of the moldboard and landside so as to hold the plow in the ground, suitable gage 25 means being provided for insuring plowing at a uniform depth. Further objects will appear from the detailed description.

In the drawings:

Figure 1 is a side view taken from the 30 moldboard side of a plow constructed in accordance with my invention.

Fig. 2 is a top plan view of the same.

Fig. 3 is a view similar to Fig. 1 the engine housing being broken away and the engine and the parts associated therewith shown in elevation.

Fig. 4 is a detail of the mounting of the drive shaft and the associated parts.

The plow is provided with a forwardly 40 projecting beam 1 carrying a standard 2 to which are secured the moldboard 3 and the landside 3^a, and the share or point 4. A housing 5 is supported by the standard and the moldboard and the landside, this 45 housing being provided with a suitable supporting frame 5^a mounted therein upon which is mounted an internal combustion engine 7, a fuel supply tank 8 being supported in the upper portion of the housing 50 and communicating with the engine through a carburetor of suitable type in the well known manner. The supply of fuel to the engine is controlled by a throttle valve rod 9 mounted upon one of the plow handles 10. 55 The engine shaft 11 is provided with a pinion 12 which meshes with a gear 13 ro-

tatable on a shaft 14 rockable in hangers 15 depending from frame 5^a. Gear 13 is provided with a sprocket wheel 14^a about which is passed a sprocket chain 15^a, this chain 60 passing about a sprocket wheel 16 secured on a shaft 17 rotatable in arms 18 which are secured, at their upper ends, on shaft 14. A drive wheel 19 is secured on shaft 17, this wheel being positioned at the center 65 of the back of the plow, between the moldboard and the landside, and being provided with a plurality of gripping elements or spikes 20. An adjusting rod 21 is mounted on handle 10 and is provided adjacent its 70 lower end with a worm 22 which meshes with a worm wheel 23 secured on the end of shaft 4 opposite to gear 13. By turning rod 21, by means of hand wheel 24 secured on the upper end thereof, wheel 19 may be 75 adjusted so as to move the moldboard and landside toward or away from the bottom of the furrow for regulating the depth of plowing.

Two standards 25, each provided with a 80 series of spaced openings 26, are positioned at opposite sides of beam 1, these standards receiving spaced supporting shafts 27 inserted through the beam, these shafts providing means whereby the standards may be 85 adjusted vertically and are held securely in adjustment. During the plowing operation, wheels 28 carried by the standards at the lower ends thereof, and a gage wheel 29 90 rotatably mounted in a depending fork 29^a at the front end of the beam 1, travel upon the ground surface, drive wheel 19 traveling in the furrow so as to propel the plow during operation of the engine. When the plow is to be transported from one field to 95 another, drive wheel 19 is rocked forwardly and downwardly so as to raise the rear portion of the plow above the ground surface, and standards 25 are lowered so as to bring the wheels 28 into engagement with the 100 ground surface, these wheels and the drive wheel acting to support the plow structure an appreciable distance above the surface of the ground, as in Fig. 1. With the plow thus supported, by rotating wheel 19 by 105 means of engine 7, the plow may be propelled so as to be readily transported from one place to another. Also, when it is desired to make a relatively shallow furrow, the wheels 28 and drive wheel 19 may be 110 utilized for supporting the plow during the plowing operation, the front gage wheel

29 being positioned above the ground surface. The adjustment of drive wheel 19 provides means whereby a furrow of the desired depth may be formed, this adjustment 5 of the drive wheel also serving to tilt the plow slightly for starting a furrow or at the end of the furrow.

In practice, it may be necessary to make slight changes in the details of construction 10 and arrangement of the different parts of my invention to accord with special conditions, and I intend to include all such variations referred to as fall within the scope of the appended claims, in this application in 15 which a preferred form only of my invention is disclosed.

What I claim is:

A tractor having a motor, a shaft, a rotatable member journaled on the shaft

driven from the motor, a second shaft, a 20 sprocket chain passing over said rotatable member, a sprocket wheel on the second shaft over which the chain passes, a frame, supporting means on the frame for the motor, a supporting wheel structure adjustable 25 from the frame, a bearing on the frame for the first shaft, arms rigid with the first shaft journaling the second shaft, a traction means on the second shaft, a worm wheel on the first shaft, and an adjusting rod having a 30 worm in mesh with the worm wheel.

In testimony whereof I affix my signature in presence of two witnesses.

JENNIE FAIRFIELD.
